[57] CLAIM

The ornamental design for a countertop video amusement device, as shown and described.

DESCRIPTION

FIG. 1 is a perspective view of a counter top video amusement device showing my new design;

FIG. 2 is a front elevational view thereof;

FIG. 3 is a top plan view thereof;

FIG. 4 is a left side elevational view thereof;

FIG. 5 is a right side elevational view thereof; and,

FIG. 6 is a bottom plan view thereof.

The broken line showing of a video screen and controls is for illustrative purpose only and forms no part of the claim.
